Ampex Corporation, Redwood City, Calif., a cor-
poration of California

Filed Feb. 24, 1967, Ser. No. 5,937

Term of patent 14 years

(Cl. D26—5)

FIG. 1

FIG. 2

FIG. 3

FIGURE 1 is a perspective view taken from the front and left side of a magnetic tape transport showing my new design, the top being in an open position, the right side being a mirror image of the left side, and the rear being conventionally plain;

FIGURE 2 is a top plan view taken on a plane parallel to that of the inclined top as shown in FIGURE 1; and

FIGURE 3 is another perspective view taken from the front and left side thereof, the top being in the closed position.

The dominant features of my design reside in the portions shown in full lines.

I claim:

The ornamental design for a magnetic tape transport, substantially as shown and described.
